My invention relates to a new and original design for a dental cabinet.

The leading features of my design consist in a dental cabinet having a body provided with suitable drawers and receptacles, one side of the body being higher than the other, forming a recess, the background of which is a mirror in a door, which covers a receptacle all arranged so as to give in conjunction with a top extension and base support an ornamental appearance.

and a downward extension of the back 3. The body is provided with drawers 4, and a receptacle closed by a door 5, a receptacle 6 having an inclined partition 7, a receptacle 8 having drawers 9, and an inner receptacle 10 30 in the body closed by the receptacle 8. At the side of the receptacle 8 is a recess 11 suitably embellished with scroll work, the background being a mirror 12 in a door 13, which covers a receptacle 14, and extending above 35 the body is a back extension suitably embellished so as to give in conjunction with the base support and body arranged as described, a pleasing and ornamental appearance to the cabinet.

40 What I claim is—

The design for a dental cabinet substantially as shown and described.

In testimony that I claim the foregoing as my own I hereby affix my signature in presence of two witnesses.
